UNITED STATES PATENT OFFICE.

HERBERT CORRAL, OF HELENSBURGH, AND JAMES MOIR FORBES, OF GLASGOW, SCOTLAND, ASSIGNORS TO THE SINGER MANUFACTURING COMPANY, A CORPORATION OF NEW JERSEY.

EMBROIDERY-SEWING MACHINE.

1,159,901.

Specification of Letters Patent.

Patented Nov. 9, 1915.

Application filed February 9, 1914. Serial No. 817,459.

To all whom it may concern:

Be it known that we, HERBERT CORRAL and JAMES MOIR FORBES, subjects of the King of the United Kingdom of Great Britain and Ireland, and residing at Helensburgh, Dumbartonshire, Scotland, and Scotstoun, Glasgow, Scotland, respectively, have invented certain new and useful Improvements in Embroidery-Sewing Machines, 10 of which the following is a specification.

This invention relates to improvements in embroidery sewing machines, and more particularly to means for locking the work-holders of a train of machines against movement while the needles are in the work, and for locking the needles in their upper position after the work holders have been released and at the completion of each stitch.

In the production of embroidery work by 20 means of two or more embroidery sewing machines the work-holder for each machine is carried by a bar or the like connected to a manually actuated pantograph device by means of which the work-holders are simultaneously operated to cause the reproduction 25 of a design by stitching.

The invention relates to a combination of elements including a tubular arm within which is journaled a rock-shaft provided 30 near one end with cam-fingers which engage a clamping-plate interposed between an opening in the tubular arm and the work-holder bar, said clamping-plate being normally spring-pressed out of engagement 35 with the work-holder bar. The rock-shaft is provided with a crank-arm which is operated from an eccentric on a driving-shaft which extends transversely of the sewing machine standards, the main-shaft within 40 each standard and the driving-shaft being connected by means of helical gears contained within an oil-casing. The aforesaid actuating mechanism for the clamping-plate is so timed with respect to the needle- 45 actuating means of each sewing machine in the train that the work-holder bar and the work-holders supported thereby are held fast throughout the movement of the needles in the work, and no strain will be imposed on the work in any attempt to shift 50 the pantograph.

The improvements afford an additional safeguard against imperfect work when it is desired to produce long filling-strokes, 55 such as those used to fill in the outline of a

leaf or an initial. In such case the stitch-forming mechanism of each machine may be automatically controlled to prevent the descent of the needles after the work-holders have been released at the completion of 60 each stitch. Thus the operator may take ample time to properly position the pantograph before he permits the needles to descend for the succeeding stitch. The means for this purpose comprise a friction disk 65 fixed to the driving-shaft, a continuously rotating driving-wheel, and means for moving said driving-wheel toward and from the friction disk, including a plural-armed rock-lever operated by a bell-crank 70 connected to a treadle device. The friction disk is provided with a stop element adapted to be engaged by one of the arms of the rock-lever when the driving-shaft and the main-shaft of each machine is so positioned that 75 the needles are above the work. By movement of the bell-crank from one extreme position to the other the rock-lever is tilted to throw the driving-wheel into operative contact with the friction disk and is then automatically released to throw one of its arms 80 into contact with the rotating disk and in position to engage its stop element when the disk completes a single rotation.

In the drawings, Figure 1 is a front perspective view of the improvements, one only of the train of embroidery sewing machines being shown, the needle of said machine being in the work. Fig. 2 is a vertical section of the same through the tubular arm of 85 the clamping device. Fig. 3 is a cross section on line $x-x$, Fig. 2. Fig. 4 is a perspective view of the clamping plate. Fig. 5 is a rear perspective of the improvements 90 showing the needle immediately prior to its descent. Fig. 6 is a perspective view of the stop-collar and trip element for the friction disk. Fig. 7 is a diagrammatic view of the 95 improvements in connection with a train of work-holders and a train of sewing machine 100 heads.

Each embroidery machine 1 is provided with the main-shaft 2 connected by means of the usual instrumentalities to needle-bar 3, and rotated by means of the helical gear-wheel 4 on main-shaft 2 engaging a similar gear-wheel 4* on driving-shaft 5, arranged transversely of the machine and supported in bearings provided by the oil-casing 6 within which said gear-wheels are received, 110

The machines are supported upon a work-table A, the frame of the work-table comprising the angle-bars *a*, *b*, *c*, connected in a suitable manner to form a rigid construction, and a work-holder 7 is provided for each machine, the work W being clamped within said holder by means of the clamping-ring 8. The work-holder is connected to a bracket 9 having a longitudinal slot 10 to receive the shank of thumb-screw 11 by means of which the work-holder is adjustably secured to a bar 12, connected at each end by means of screws 13 to a section of the pantograph device B, B', said device being secured to guide-bar 14 of the usual construction.

The work-holder bar is actuated above the friction face 15^x of a bracket 15 secured at one end by means of screws 16 to angle-bar *b* and at its opposite end secured by means of screw 17 to angle-bar *c*. Overlying the work-holder bar and extending transversely of the work-table is a tubular arm 18 provided near its rear end with seats 19 to receive center-screws 20 entering apertures formed in the upwardly extending arms 21 of a bracket-support 22 secured to a plate 23 supported by the work-table. Within the tubular arm and supported by bearings 24, 25 and 26 is a rock-shaft 27 provided at its rear end with a crank-arm 28 formed with an aperture to receive an eccentric rod 29 and pressed downwardly into engagement with stop-nut 30 on said rod by means of helical-spring 31. The eccentric rod is provided with a strap 29^x which embraces an eccentric 32 on driving-shaft 5 from which rocking movements are imparted to the shaft 27. It will be seen that manipulation of stop-nut 30 will effect a circular adjustment of the rock-shaft.

The tubular arm is provided with an opening between bearing members 25 and 26 to receive a clamping-plate 33 provided with a friction face 33^x to engage the work-holder bar 12. The clamping-plate is provided also with a hub 34 disposed intermediate apertured lugs 35 and 36 on the tubular arm, 18, said lugs receiving a pin 37 which enters the hub 34 and pivotally connects the plate with the tubular arm. The clamping-plate is normally elevated out of engagement with the work-holder bar by means of a spring 38 coiled around pin 37 and seated within an aperture formed in lug 35, one end of the spring being connected to the tubular arm and the opposite end of said spring being seated within an aperture 39 formed in the clamping-plate.

In its front end the tubular arm is provided with spaced lugs 40 to receive a pin 41 pivoted between lugs 42 on bracket 15 and provided with thumb-nut 43 by which the foot 18^x of the tubular arm is pressed

upon the upper face of bracket 15 and the arm held firmly against movement. It will be seen that the tubular arm may be tilted upwardly upon center-screws 20 when the thumb-nut 43 is loosened and the pin 41 retracted.

Rotation of driving-shaft 5 will transmit reciprocating movements to the needle-bar 3 and the needle clamped thereto. It will be seen that each rotation of the driving-shaft will cause the eccentric 32 to impart a rocking movement to shaft 27 and thereby carry the cam-fingers 27^x on said shaft into engagement with the clamping-plate 33 to press the friction face of the latter into engagement with work-holder bar 12 during the time the needles are in the work, a second movement of the rock-shaft retracting the clamping elements as the needles rise above the work.

The driving-shaft has fixed thereon a friction disk 44 provided with a hollow hub 45 projecting beyond the end of the driving-shaft, and thus providing a chamber to receive a coiled spring 46 which rests between the end of the shaft and the head of a pin 47, the latter being pressed upon the hardened steel cap 48 of a driving-wheel 49 loosely fitted upon said projecting hub of the disk. The spring 46 acts normally to disengage the face of the driving-wheel from contact with a ring of friction material 50 fitted within an annular groove formed in the inner face of the friction disk. The driving-wheel is provided with the usual peripheral groove 49^x to receive driving-belt 51 connected by suitable means to a motor or other power device.

In Fig. 5 the machine 1^x is the first of the train of embroidery machines, and the oil-casing 6, which incloses the operating gear-wheels 4 and 4^x for the machine, is formed integrally with a bracket 52 secured to the sewing machine standard by means of a screw 53 and provided with a laterally projecting foot which affords a support for the plural-armed operating rock-lever 54, said lever being pivoted upon the bracket foot by means of a stud-screw 55 which enters an aperture formed within the hub 56 of said lever, the enlarged head of said screw serving to confine upon said hub the sleeve 57 of a brake-arm 58 provided with a brake-shoe 59 adapted to contact with the inclined surface 60 upon the friction disk. The brake-arm rests upon the end of a screw 61 adjustable within boss 62 upon one arm *b* of the rock-lever. The arm *a* of the rock-lever is enlarged at its extremity and provided with a socket to receive a spring plunger-pin having a rounded head 63 which is disposed adjacent the cap 48 of driving wheel 49. It will be seen that the movement of rock-lever 54 to the left from the position shown in Fig. 5 will carry the plunger-pin 120

away from the driving-wheel, thus permitting the spring 46 to move said wheel out of operative engagement with the friction disk, it being apparent that such movement of the lever will carry brake-arm 58 in position to engage inclined space 60 of the driving-wheel. The reverse movement of lever 54 will move the driving-wheel axially against the pressure of spring 46 and into frictional engagement with the disk, whereby motion will be transmitted to the main-shaft of each sewing machine.

To stop the friction disk at a definite point so that the driving-shaft and the main-shaft of each machine are positioned to hold the needles above the work, the disk is provided with an annular chamber 64 surrounding its hub, and adapted to receive coiled springs 65, one end of each spring being connected to a pin 67 secured to the disk, and the opposite ends of the springs being connected to a pin 68 passing through a concentric slot 69 formed in the disk and being fixed to the flange 70 of a collar 71 loosely mounted upon the hub 45 of said friction disk and normally rotating therewith. The flange 70 of said collar is cut away to provide a gap and opposed shoulders 70*. When lever 54 is rocked to stop the machines, a trip-element 72 upon one arm *b* of the rock-lever enters the gap formed in the flange of collar 71 and engages one of the shoulders 70*, whereby the collar is held against rotation and the momentum of the friction disk is overcome by the compression of one spring and the expansion of the second spring, aided by the action of brake 58.

The operating means for rock-lever 54 comprises a bell-crank 73 pivoted by means of stud-screw 74 to a bracket 75 secured to the work-table A, said bell-crank being provided with a roller 76 adapted to engage the point of a pin 77 secured to the outer extremity of the arm *c* of lever 54. To the bell-crank is secured the upper end of a rod 78 operatively connected at its lower end to a treadle-device of any suitable construction. A spring 79 secured to the table and connected to the rock-lever tends to tilt the latter to carry arm *a* out of engagement with the driving-wheel and the brake and trip elements into engagement with the friction disk.

It will be seen that the bell-crank 73 in its mid-way position, as shown in Fig. 5, will hold arm *c* of the rock-lever elevated and the driving-wheel in operative engagement with the friction disk and thus will effect a continuous operation of each machine while it remains in such position. To cause the machines to be stopped automatically at the termination of each stitch, the bell-crank 73 is moved from one extreme position to the other, whereby the roller 76 engages the pin 77 on arm *c* of the lever 54, and causes the

spring plunger carried by arm *a* to engage the cap 47 on driving-wheel 49, the latter being moved axially against the action of spring 46 so that its face is brought into operative engagement with the friction disk. 70 The roller 76 in reaching its extreme position passes pin 77 and permits the lever to be tilted by spring 79 toward the left from the position shown in Fig. 5, thus carrying the trip-element 72 into contact with the 75 flange of collar 71. When the disk in completing one revolution has caused the stitch-forming mechanism to produce a stitch and the needles to rise above the work simultaneously with the release of the work-holder 80 clamp, the gap in collar 71 comes into register with trip-element 72, and the latter moves into said gap simultaneously with the application of brake-arm 58 to the rotating disk, whereby further rotation of the disk is prevented, as hereinbefore described.

It will be understood that the driving-shaft 5 for the train of machines may be formed in sections, the sections being connected by coupling bars 79 or the like. It 90 is evident also that a cam may be substituted for eccentric 32, and that various changes may be made in the construction and arrangement of the parts without departing from the spirit of the invention. 95

Having thus set forth the nature of the invention, what we claim herein is:—

1. In embroidery sewing machines, the combination with a train of sewing machine heads each head containing a main-shaft 100 and operating parts for stitch-forming mechanism, of a train of work-holders, a pantograph, a supporting-bar connecting said work-holders and the pantograph, a driving-shaft adapted to actuate the main-shaft of each machine head, and means controlled by said shaft for holding said supporting-bar motionless during periods* of the stitch-forming operations.

2. In embroidery sewing machines, the combination with the driving shaft, a frame, a rock-shaft supported for bodily movement upon said frame, and operative connections between said shafts, of a work-holder, means for supporting said work-holder, including 110 a movable bar, clamping means for said bar including a member movable with said rock-shaft, and a latch device adapted to hold the rock-shaft against bodily movement.

3. In embroidery sewing machines, the combination with a driving shaft, a rock-shaft and operative connections between said shafts, of a bodily movable carrier for said rock-shaft and a latch device adapted to 125 hold said carrier against movement, a work-holder, a movable bar adapted to support said work-holder, a pantograph connected to said bar, and means for periodically clamping said bar including a fixed pressure-sus- 130

taining member and a clamping member controlled by said rock-shaft and bodily movable therewith.

4. In embroidery sewing machines, the combination with a driving-shaft, a rock-shaft, and operative connections between said shafts, of a tubular arm within which said rock-shaft is journaled, a work-holder, means for supporting said work-holder including a movable bar, a pantograph connected to said bar, and means for periodically holding said bar motionless including a cam-finger upon said rock-shaft.

5. In embroidery sewing machines, the combination with a driving-shaft, a rock-shaft, and operative connections between said shafts, of a tubular arm within which said rock-shaft is journaled, a work-holder, means for supporting said work-holder including a movable bar, a pantograph connected to said bar, and means for periodically holding said bar motionless including a fixed clamping member, a clamping-plate movable toward and from said fixed member, a spring engaging said clamping-plate and means carried by said rock-shaft for moving said plate against the action of its spring and toward said fixed clamping member.

6. In embroidery sewing machines, the combination with a driving-shaft, a rock-shaft and operative connections between said shafts, of a work-holder, a supporting-bar, means for adjustably connecting the work-holder and the supporting-bar, a pantograph device connected to said bar, a tubular arm within which said rock-shaft is journaled, a pivotal support for said tubular arm, means for locking said arms against movement, a clamping-plate overlying and normally spring-pressed out of engagement with said supporting-bar, and means carried by said rock-shaft for periodically moving said clamping-plate to engage said bar and to hold the same motionless.

7. In embroidery sewing machines, the combination with a driving-shaft and a rock-shaft, of a crank-arm on said rock-shaft, operative connections between said driving-shaft and the crank-arm including

a reciprocating rod and means for adjusting said crank-arm relatively to the rod, of a tubular arm within which said rock-shaft is journaled, a movable clamping-plate supported by said tubular arm, a cam carried by said rock-shaft and engaging the clamping-plate, a spring for pressing said plate toward the rock-shaft, a work-holder, a supporting-bar for said work-holder, a pantograph connected to said bar, and a fixed clamping member against which the bar is periodically pressed by the action of said movable clamping-plate.

8. The combination with a train of embroidery sewing machines, each including a needle and means for reciprocating the same, of a series of work-holders, a pantograph, a bar connecting said work-holders and the pantograph, means acting on said bar at the descent of each needle, and serving to prevent movement of the pantograph during the time the needles are in the work, and means whereby the needles may be locked above the work after the work-holders have been released and at the completion of each stitch.

9. In embroidery sewing machines, the combination with a train of sewing machine heads, each head supporting a main-shaft, a needle, and needle-reciprocating means, of a train of work-holders, a pantograph, a supporting bar connecting said work-holders and the pantograph, a driving-shaft adapted to actuate the main-shaft of each machine head, automatically acting means operatively connected to said driving-shaft whereby said work-holders are held motionless while the needles are in the work, and means connected to said driving-shaft for preventing the descent of each needle after the work-holders have been released and at the completion of each stitch.

In testimony whereof we have signed our names to this specification in the presence of two subscribing witnesses.
